UNITED STATES PATENT OFFICE.

WALTER T. KRAUSCH, OF LA GRANGE, ILLINOIS, AND ERNST F. WEBER, OF CRESTON, IOWA.

TRACK-LAYING CAR.

1,248,676.

Specification of Letters Patent.

Patented Dec. 4, 1917.

Application filed June 12, 1916. Serial No. 108,239.

To all whom it may concern:

Be it known that we, WALTER T. KRAUSCH and ERNST F. WEBER, citizens of the United States, and residents of La Grange, in the county of Cook and State of Illinois, and of Creston, in the county of Union and State of Iowa, respectively, have invented certain new and useful Improvements in Track-Laying Cars, of which the following is a description, reference being had to the accompanying drawings, which form a part of our specification.

The invention relates more particularly to a car for handling and laying railway rails in position on the ties; the invention contemplating the type of device which is more especially adapted to move or run on rails previously laid thereby and to pick up other rails which have been distributed along the side of the road-bed or track.

The invention relates to a track-laying machine or car provided with proper motive power for propelling the car along the rails and also for operating the means whereby the rails are lifted and lowered into proper position preparatory to being fastened or spiked to the ties; the construction of the car being such that the operation may be controlled by a single operator, as will be more fully understood from the following detailed description from which the advantages of our construction will be readily apparent.

In the drawings:

Fig. 1 is a sectional plan view of the car with all of the mechanism located above the floor removed and the front end of the car broken away.

Fig. 2 is a similar view of the front end of the car.

Fig. 3 is a detail view illustrating the windlass and driving mechanism in elevation.

Fig. 4 is a longitudinal sectional view of the car and the mechanism located above the floor, the view being taken substantially on the line 4-4 of Fig. 1.

Fig. 5 is a longitudinal sectional view of the front end of the machine, to wit, the portion located forward of that disclosed in Fig. 4, and shown in Fig. 2, with the mechanism located thereon shown in elevation; portions of said mechanism being broken away.

Fig. 6 is a detail sectional view taken on

the line 6-6 of Fig. 5 looking in the direction of the arrows.

Fig. 7 is a detail sectional view taken on the line 7-7 of Fig. 5.

Fig. 8 is a detail perspective view of one of the transversely arranged transporting members or wheels.

The invention is disclosed in the form of a power-driven car composed of suitable side sills 10, 10 secured together by end sills 11, 11 and also provided with suitable intermediate sills 12, 12 at the rear end of the underframe of the car; the sills 12, 12 being shown secured to the transverse sill 13, which in turn is secured to the side sills 10, 10, see Fig. 1.

The intermediate sills 12, 12 provide suitable support for a motor indicated at 14 in Fig. 4, illustrated in the form of a well known type of internal combustion motor 75 provided with a suitable radiator indicated at 15 in Fig. 4. The motor or crank shaft is shown provided with the usual fly-wheel 14' while the outer end is provided with a suitable sprocket 16 whereby the power-shaft 17, suitably hung or journaled beneath the underframe of the car, is driven through the medium of sprocket chain 18. The power-shaft 17 is provided with a sprocket wheel 19 in alignment with sprocket 16 to receive the sprocket chain 18; the power-shaft extending toward the front end of the car, as clearly shown in Fig. 2.

The forward end of the power-shaft 17 is provided with a miter gear 20 adapted to mesh with the miter gears 21 and 22, both of which are loosely mounted on the front journal 23 of the car to which the front wheels 24, 24 are secured. Miter gear 21 is controlled by a suitable clutch mechanism 95 25, while the miter gear 22 is controlled by a similar clutch mechanism 26, both of which are mounted on the front journal or axle 23, and adapted to provide operative relation between the gears and the journal, as shown in Fig. 2. The clutch mechanisms are of a well known type of construction, and therefore will require no specific description.

The clutch mechanism 25 is controlled by lever 27 pivoted at 28 to the end sill of the car underframe so as to swing laterally; while the clutch mechanism 26 is controlled by a similar lever 29 pivoted at 30 to the end sill of the car underframe, as shown in Fig. 2. The opposite ends of both levers 27 and 110

29 are pivotally connected to the connecting link 31, shown in dotted lines in Fig. 2, and have operative relation with bell-crank lever 32 which is pivotally secured at 32' to the 5 car underframe, so that movement of the bell-crank lever will simultaneously move both clutch mechanisms, the one into and the other out of operative position. Pivotally secured to the bell-crank lever 32 is 10 a reach-rod 33, the other end whereof is pivotally secured to the hand-lever 34 mounted on the stub-shaft or rod 35, see Figs. 1 and 4.

With the construction shown, when hand lever 34, shown in Fig. 4, is moved forward, reach-rod 33 will cause bell-crank lever 32 to swing in a direction which will induce link 31 to move lever 27 toward power-shaft 17 and thus cause clutch mechanism 25 to provide operative relation between miter gear 21 and the front journal or axle 23. During such movement, it is clearly evident that clutch mechanism 26 will be moved out of operative relation with miter gear 22, so 25 that the power from power-shaft 17 will cause the car to travel forwardly. Movement of hand lever 34, backward from the normal position shown in Fig. 4, will induce bell-crank lever 32 to rock forwardly and thereby cause clutch mechanism 26 to provide operative relation between miter gear 22 and the journal or axle 23 and at the same time throw clutch mechanism 25 out of operative relation, so that the car may be moved in the opposite direction through the action of power-shaft 17.

At a point forward of the motor 14, and in close proximity to operating lever 34, the machine or car is provided with a suitable 40 operator's seat 35', see Fig. 4.

The car underframe, at a point near the front end thereof, is shown provided with transversely disposed reinforcing Z-bars 36, see Figs. 2 and 5. These transversely extending members provide suitable support for the bearing plates or members 37 whereby the tension post or mast 38 is suitably maintained in proper position. The mast 38 may be of any suitable formation or construction, being shown as preferably composed of channel irons, see Figs. 5 and 6, provided with a bottom post adapted to extend into a suitable opening in the top bearing-plate. The bottom post provides a 55 suitable attaching point for the swivel or bearing member 39 whereby the boom 40 is given proper pivotal bearing on the mast. The means employed for securing the boom in place is such that the boom may be 60 quickly detached through the removal of a pin adjacent the bottom end of the post or mast 38. The boom 40 is preferably constructed of two parallelly arranged channel-irons, between which is riveted a proper boom-bearing member or forging 41 pro-

vided with a suitable socket to fit about the post at the lower end of the main post or mast; and the sides of the boom are provided with clamping members 42 secured to the sides of the boom by suitable rivets, 70 which also secure the bearing or forging 41 in place; the clamping members are shown extending to the rear of the main post or mast 38 where the ends are clamped together by the bolt 43.

The top of the main post or mast 38 is provided with a suitable center pin 44, properly secured in place and provided with an attaching member 45, to which the truss-rod 46 is secured; the opposite end 80 of the rod being pivotally secured to the outer end of the boom, as shown in Fig. 5. The truss-rod is shown provided with a suitable turnbuckle 47 for maintaining proper tension. The opposite end of attaching member 45 is adapted to receive the truss-rod 48 which, by means of turnbuckle 49, is fastened to attaching member 50 secured to the platform or underframe of the car, as shown in Fig. 4.

The outer end of the boom 40 is provided with a suitable sheave 51, see Fig. 5, about which cable 52 extends; the outer end of the cable being provided with the loosely mounted or traveling sheave 53, which is provided with a suitable housing 54 shown provided with an attaching eye or any other suitable attaching means; while the end of the cable 52 is secured to the link 55 by means of suitable clips 56; the link 55 in turn being 100 secured to the end of the boom, as shown in Fig. 5, thus permitting the cable to be "played out" in the usual manner.

The cable 52, after passing over sheave 51, extends between the correlated sheaves 57, 105 57 which are maintained in the inclined, transverse position indicated in Fig. 5 by means of a suitable bracket 58 secured to the main post or mast 38. These sheaves 57 permit the hoisting cable 52 to pass between the members constituting the main post or mast 38 without forming frictional contact with the mast, as clearly shown in Fig. 6, and therefore prevent the cable being cut or worn, and at the same time maintain the 115 cable in proper position relative to the drum 59 of the windlass shown in Fig. 4.

The windlass is arranged at a suitable point preferably rearward of the mast 38; the supporting posts 59, 59 whereof, see Fig. 3, are secured in any suitable manner to the car underframe.

The drum is provided with a suitable gear 60 adapted to mesh with pinion 61 keyed to shaft 62 rotatably mounted in the supports 125 or posts 59. The power-shaft 17, at a point substantially in vertical alignment with the windlass, is shown provided with cone-pulleys or friction wheels 63 and 64 slidably keyed to the shaft 17. The cone-pulleys or 130

- frictional wheels 63 and 64 are controlled by means of levers 65 and 66; one end of each lever being pivotally secured to the car-underframe, as shown in Fig. 1, while the other 5 end of each lever is pivotally connected to the reach-rod 67 which extends rearward to a suitable operating lever 68 pivotally mounted on the stub-shaft or axle 69 and disposed adjacent the operator's seat. Rotatably mounted on the car underframe is a shaft 70, the end whereof is provided with a cone-pulley or friction-wheel 71 adapted to form frictional engagement with cone-pulleys or frictional wheels 63 and 64. The shaft 70 is 10 provided with a suitable sprocket 72 which receives sprocket-chain 73 which, in turn, extends about the sprocket-wheel 74 mounted on the shaft 62. Movement of hand-lever 68 rearward will cause reach-rod 67 to force cone-pulley or friction-wheel 63 into frictional engagement with the cone-wheel 71, while friction-wheel 64 is slid out of operative engagement, thereby inducing the power-shaft 17 to drive the windlass in winding direction so as to take up hoist-cable 52. Movement of hand lever 68 forwardly, or in opposite direction, will draw reach-rod 67 backward, throw cone-pulley or friction wheel 63 out of frictional engagement with cone 71, and move cone-pulley or friction-wheel 64 into frictional engagement with frictional wheel 71, and cause the windlass to move in the opposite or unwinding direction.
- 15 In order to brake or lock the windlass, the shaft 62 is provided with a brake-wheel 75, about which band-brake 76 extends, one end of the band-brake being permanently secured to the transversely disposed rod 77, while the other end of the band-brake is secured to the link 78, pivotally mounted on rod 77, with its lower end pivotally secured to reach-rod 79 attached to the lower end of foot-lever 80 which is pivotally mounted to the car underframe and extends through a suitable opening in the floor of the car so as to be readily accessible and in easy reach of the operator's seat 35.
- 20 With hand lever 68 in vertical or neutral position, the friction-drive mechanism, composed of friction-wheels 63, 64 and 71, will be out of mesh or operative relation, thus enabling the windlass to be independently operated should it be so desired. To permit such operation of the windlass, at times when the motor may not be in operation, we have shown the windlass provided with the hand-operating shaft 81 arranged transversely of the windlass frame and provided 25 with the usual cranks 82, as shown in Fig. 3. The shaft 81 is mounted so as to have movement transversely of the windlass, and is provided with a pinion 83 adapted to mesh with gear 69 when shaft 81 is moved to the right in Fig. 3. Shaft 81 is provided with
- 30 a suitable collar or flange 84 which is intended to be engaged by the detent or pawl 85 pivotally mounted at 86 so as to permit the pawl or detent to be moved vertically out of the path of the flange or collar 84. As is evident from the construction shown, the detent or pawl 85 engages with the flange or collar 84 and prevents longitudinal movement of shaft 81. When it is desired to operate the windlass by hand, pawl or detent 85 must be lifted in order to shift the shaft 81 to the right in Fig. 3, after which the detent or pawl is allowed to drop into engagement with the opposite side of the flange or collar 84 and thereby prevent the shaft moving in a direction which would throw pinion 83 out of mesh with gear 69.
- 35 The front part of the car underframe is shown provided with a suitable yoke or strap 87 provided with a suitable opening 88 to receive any suitable coupling means, as shown, for example, in Fig. 5.
- 40 Suitably mounted on the transversely extending shaft, on which foot-lever 80 is pivotally secured, is a second foot lever 88, 90 extending through a suitable opening in the car floor, and provided with a reach-rod 89. The other end of the lever is connected with the lever 90 to which one end of band-brake 91 is secured, while the other end of the lever 95 is pivotally mounted on the rod 92, to which the opposite end of the band-brake is also secured. The band-brake 91 is shown encircling a suitable brake-wheel 93 secured to rear journal or axle 94 to which the rear 100 wheels of the car are secured. In addition to the braking-means just described, we show the machine also provided with a hand-operated brake controlled by means of the hand-lever 95 pivotally secured to the car 105 under-frame and provided with a reach-rod 96 extending to the rocking-beam 97, to the opposite end whereof is secured reach-rod 98 which controls the brake-shoe beam or rod 99 linked to or supported on the car- 110 frame in any suitable manner.
- 45 Extending transversely of the car or machine are a pair of I-beams 100 and 101; the beam 100 being slidably held in place by means of suitable brackets or yokes 102 115 arranged on the upper side of the car-underframe; while the I-beam 101 is supported by means of suitable brackets or yokes 103 preferably disposed on the under-side of the car-frame, because of the location 120 of the motor at this end of the car. The beams 100 and 101 may be of any suitable shape in cross-section and are intended to provide suitable support for a ballast rail, beyond the sides of the car, as shown at 104 125 in Fig. 1. The ballast rail 104 may be supported or held in place on the ends of the supporting beams by suitable straps or brackets. The supporting rails 100 and 101 are adapted to slide transversely of the ma- 130

chine in order to extend beyond either side of the car, a distance sufficient to make the ballast rails effective; the latter being applied on the side of the car opposite to the side toward which the boom is being swung to lift rails.

The motor and operator's end of the car is shown provided with a suitable canopy 105 of any suitable construction and supported by suitable uprights which may be secured to the car underframe in any well known manner. The bottom of the seat is provided with a suitable tool-chest or box, as indicated at 106 and also with a battery chamber or box 107 in which a suitable battery for connection with the spark coil and magneto of the motor may be arranged.

As is clearly evident from the construction, a single operator can control both the movement of the car relative to the road-bed or track and also operation of the windless whereby movement of the rails into place is accomplished. Our improved construction therefore obviates the necessity of employing a number of operators or men to manipulate the windless, as is the case with the track-laying machines at present in use; and merely one or two men need be employed to secure the unlaid rail-section to the traveling sheave mounted on the hoist-cable.

At suitable points, as for example, intermediate of the rail-engaging wheels 24, we prefer to provide the side sills 10 with suitable brackets, preferably composed of the downwardly presented members 108, 108 properly riveted or otherwise secured to the side sills, as more clearly shown in Fig. 8; the four brackets, as shown in Fig. 1, preferably each consisting of the pair of spaced members 108 in order to receive between them the wheel-carrying bell-crank lever or member 109. The brackets and levers 109 at all four points on the car-frame are similar in construction. The bell-crank member 109 is provided with a hub-portion 110 mounted intermediate of the bracket-members 108 and is pivotally secured in place by the belt 111 so as to permit member 109 to be swung vertically. The inner or lower end of member 109 is preferably bifurcated as shown so as to receive the wheel 112, rotatably mounted in place by means of a suitable bolt or pin 113; the wheels 112 being preferably provided with a flat rim or felly in order to more properly adapt them for the purpose hereinafter mentioned. The opposite or outer end of member 109 is socketed, as shown at 114 in Fig. 8, so as to receive any suitable rod or lining bar when it is desired to force the wheel-carrying members into operative position. The wheels 112 are set transversely of the car-frame, as very clearly shown in Fig. 1, and are intended for use when it is desired to

take the car or machine off the track for the purpose of clearing the same for trains, especially in places where a switch or side track is not available. In order to provide for proper application of power, the member 109 is preferably shaped as shown and described in order that the free or outer end provided with the socket 114 may be presented downwardly as shown when the members are in raised or in inoperative position, in order that, through the use of a proper rod or bar, sufficient lifting power may be exerted on member 109 in order to force the wheel ends of member 109 into substantially vertical position and force the wheels 112 into contact with suitable planks disposed transversely between the rails and at the sides of the track, so that the car may be lifted sufficiently to free the flanges of the rail-engaging wheels 24, and thus permit the car to be moved transversely of the truck. In order to maintain the wheel-holding members 109 in either operative or inoperative position, the bracket-members 108 are shown provided with correlated perforations 115 adapted to receive suitable bolts or pins; the bolts or pins being passed through the proper pair of holes so as to engage with opposite sides of the socketed end of member 109, as will be readily understood. With the arrangement shown and described, the machine or car can be quickly removed from the track by two men and thus clear the right of way.

We endeavored not to encumber the specification with descriptions and illustrations of modifications of our invention; having shown and described what we believe to be the simplest and best form; it being understood, however, that modifications may be made in certain details of construction, without, however, departing from the spirit of our invention.

What we claim is:

In a track-laying car of the class described, a main post or mast mounted on the car and composed of parallelly arranged members secured together in spaced relation with an extension post between at both ends, both posts being provided with cylindrical portions at points intermediate of their ends, bearing-plates secured to the car adapted to receive the extension-post at the bottom of said mast and arranged to maintain the latter against rotation, a boom composed of parallelly arranged members provided at the lower ends with a bearing-member there-between adapted to bear against the cylindrical portion of the post at the bottom of the mast, a pair of clamping members secured lengthwise of said boom-members and said bearing-member adapted to extend on opposite sides and rearward of the lower extension post of said mast whereby the boom is removably

secured to the mast and permitted to swing laterally, the boom being provided with a sheave at its outer end, a truss-member pivotally secured adjacent the outer end of the boom and to the cylindrical portion of the extension post at the upper end of the mast so as to permit lateral movement of the boom, in combination with a windlass secured on the car rearward of the mast and 10 having a cable extending between the par-

allelly arranged members of the mast and over the sheave at the outer end of the boom, with its end secured to said boom, said cable being provided with a traveling sheave.
